The ornamental design for a growth control device, as shown and described.

DESCRIPTION

FIG. 1 is a front perspective view of a growth control device in accordance with a first embodiment of the present invention;

FIG. 2 is a top plan view of the growth control device shown in FIG. 1;

FIG. 3 is a right side elevation view of the growth control device as oriented in FIG. 2, the left side elevational view being a mirror image thereof;

FIG. 4 is a bottom plan view of the growth control device shown in FIG. 1;

FIG. 5 is a right side elevation view of the growth control device as oriented in FIG. 4, the left side elevational view being a mirror image thereof;

FIG. 6 is a front end elevation view of the growth control device shown in FIG. 1; and,

FIG. 7 is a rear end elevation view of the growth control device shown in FIG. 1.

It will be understood that the broken lines shown in FIGS. 1-7 illustrate structure associated with the present invention but form no part of the claimed design.
